UNITED STATES PATENT OFFICE.

THEODORE G. JOHNSON, OF KANSAS CITY, MISSOURI.

PAINT MIXING AND GRINDING MACHINE.

SPECIFICATION forming part of Letters Patent No. 532,277, dated January 8, 1895.

Application filed February 15, 1894. Serial No. 500,199. (No model.)

To all whom it may concern:

Be it known that I, THEODORE G. JOHNSON, of Kansas City, Jackson county, Missouri, have invented certain new and useful Improvements in Paint Mixing and Grinding Machines, of which the following is a full, clear, and exact description, reference being had to the accompanying drawings, forming a part hereof.

10 My invention relates to paint mixing and grinding machines, and has for its object to produce a machine of this character, wherein the paint is thoroughly mixed, and other force besides gravity is employed to feed the mixed paint to the grinder, so that the paint may be ground more quickly and finely than when the specific gravity of the paint, alone, is depended upon; wherein the force employed may be doubled to double the quantity of paint fed to the grinder in the same space of time, so that it may be ground and forcibly ejected or discharged from the machine, in about half the time employed in the operation first referred to, wherein the 15 grinder is adjustable to regulate the fineness of the ground paint, and finally to produce a paint mixing and grinding machine which is simple, strong, durable, and inexpensive of construction.

20 With these objects in view the invention consists in certain peculiar and novel features of construction and combination of parts, as hereinafter described and claimed.

In order that the invention may be fully understood, reference is to be had to the accompanying drawings, in which—

Figure 1. is a perspective view of a paint mixing and grinding machine, constructed in accordance with my invention. Fig. 2. is a 25 vertical sectional view taken on the line $x-x$ of Fig. 1. Fig. 3. is a vertical sectional view taken on the line $y-y$ of Fig. 1, and showing the grinding mechanism in elevation. Fig. 4. is a detail perspective view of the grinder.

30 In the said drawings, a box is formed with a flaring mouth or open end 1, and a semicylindrical cavity 2, forms its bottom or lower end; which cavity extends horizontally and transversely of the box. The box is also enlarged semicylindrically at each side and above the semicylindrical cavity 2; which forms the op-

positely disposed and horizontal semicylindrical cavities 3 and 4. These cavities are interposed between and communicate with the mouth 1, and the cavity 2, and they also extend transversely of the machine. The center of the cavity 2, is positioned a little to one side of the medial line of the machine, for a purpose hereinafter explained. This box is preferably cast in two parts; one part consisting of a side and two end-walls, and the other part of the opposite side, which is detachably secured to the end-walls. A packing 6, is also interposed between the detachable side and the end-walls, so as to form a joint which will not permit of leakage. Depending divergently from each side of the bottom of the box, are legs 7, and these legs are secured by screws or other suitable means, upon a work-bench, or in other suitable or convenient position. Extending axially through the semicylindrical cavity 3, is a shaft 8, which is journaled in the side-walls of the machine, and this shaft carries upon its projecting end, a handle 9, of any suitable or preferred construction. Keyed, or otherwise rigidly mounted upon the shaft 9, and fitting so snugly within the cavity 3, as to almost touch the walls thereof, is a ribbed roller or cog-wheel, 10. Extending axially through the 35 semicylindrical cavity 4, is a shaft 11, which is journaled in the side-walls of the machine and keyed or otherwise rigidly mounted upon said shaft, and fitting so snugly within the cavity 4, as to almost touch the inner walls thereof, is a ribbed roller or cog-wheel 12, which meshes with the roller or cog-wheel 10.

Cast integral with, and projecting inward from the lower end of the side and upwardly from the bottom of the box, and centrally of the cavity 2, is a lug 13, and this lug is formed at its inner face, with a horizontal and transversely extending cylindrical cavity or recess 14; said cavity or recess extending axially of the center of the cylindrical cavity 2. The 40 detachable side of the box is formed with an outwardly projecting and conical shell or nozzle 15, which is concentrically arranged relative to the axial center of the semicylindrical cavity 2, and adjustably engaging a screw-threaded aperture formed in the outer end of the said conical shell, is a set-screw 16, which

is longitudinally aligned with the center of the cylindrical cavity or recess 14. The shell 15, is also provided near its outer end and lower side with an exit opening or spout 17.

5 The grinder mechanism consists of the conical portion 18, which fits within the conical shell 15, and the spindle or shaft 19, which projects axially from the center of the cone, and engages revolubly at its free end, the 10 cylindrical cavity or recess 14. The cone is formed at its opposite end with a cylindrical recess 20, which is engaged by the inner end of the set-screw 16; which thus forms one bearing, while the cylindrical cavity or recess 14, forms the other bearing for the grinder 15 mechanism. Cast integral with, or keyed securely upon the shaft or spindle 19, is a gear-pinion 21, and this gear-pinion engages or meshes with the ribbed roller or cog-wheel 10 20 alone; owing to the fact that its shaft 19 is located to one side of the center. Adjustably secured in a screw-threaded opening formed through the lug 13 in the adjacent side of the box, is a set-screw 22, and the inner end of this set-screw bears against the adjacent end of the spindle or shaft 19. From this construction it will be apparent that by the proper operation of the set-screws 16 and 22, the annular space between the 25 grinding surface of the cone and the grinding or inner surface of the shell 15, may be increased or diminished at will, so as to regulate or determine the degree of fineness to which the paint is ground.

30 In the operation of the machine, the oil and paint is poured into the open upper end or mouth of the box. The handle 9 is then operated, so as to turn the rollers in the direction indicated by the arrows, Fig. 2, and this rotation of the rollers not only thoroughly agitates and mixes the paint and oil, but also performs the function of a force pump, in precipitating the paint to the bottom of the box, because each rib of the inwardly moving 35 rollers gathers a certain quantity of paint, and forcibly separating it from the mass in the upper end of the box, carries it downward and discharges it into the cavity 2 at the bottom of the box. These engaging ribs not 40 only tend to force the paint to the bottom of the box, but also operate to grind the paint from frictional contact, as will be readily understood. By the revolution of the rollers 10 and 12, the pinion 21, is also caused to 45 rotate, and by revolving the cone 28 rapidly in the shell, the paint forced between said cone and shell by gravity and by the pump action of the rollers, is ground thoroughly, and is discharged or ejected forcibly from the exit 50 opening 17, into a paint bucket, or other suitable receptacle placed for the purpose below said opening.

If it is desired, without further adjustment of the grinding mechanism, to grind the paint 55 more quickly and finely, the handle 9, is turned to rotate the rollers 10 and 12, in the

direction opposite to that indicated by the arrows, Fig. 2. This operation, instead of causing the teeth of each roller alternately to carry down a quantity of paint, causes 70 each tooth of each roller to carry down simultaneously an equal quantity of the paint, so that with each complete revolution of the rollers, double the quantity of paint is carried to the bottom by the latter method of rotation than by the former, and as this paint must have an exit, it is compressed or forced more tightly between the revolving cone and the shell; is there more finely ground, and is more quickly and forcibly ejected from the 80 exit opening 17. In this latter operation, the paint is also subjected to a grinding operation, owing to the proximity of the inner side of the semicylindrical walls forming the cavities 3 and 4 and the faces of the toothed 85 rollers.

By forming the box, with the semicylindrical cavities 3 and 4, shoulders are formed at the junction of the said cavity end-walls, and the walls forming the lower end of the mouth 90 or opening 1, and these shoulders tend to cause all of the paint to settle down between the rollers or cog-wheels 10 and 12, so that little or no paint can reach the bottom of the box without first passing between said rollers, 95 unless said rollers are rotated in the direction opposite to that indicated by the arrows, and this construction thereby insures a thorough mixing of all the paint placed within the machine.

100 From the above description, it will be seen that I have produced a paint mixing and grinding machine, which thoroughly mixes and grinds all of the paint in the shortest space of time, and which is simple, strong, durable, and inexpensive of construction.

Having thus described my invention, what I claim as new, and desire to secure by Letters Patent, is—

1. In a paint mixing and grinding machine, 110 the combination with a box, engaging rollers mounted therein, and a conical recess communicating with the lower end of said box, and having an exit opening, of a pinion rotatably mounted in the lower end of said box, 115 and meshing with one of the first-mentioned rollers, and a conical grinding surface, fitting in said conical recess, and means to actuate or rotate the conical grinding surface and the said rollers, substantially as set forth.

2. In a paint mixing and grinding machine, 120 the combination with a box, a recess communicating with the interior of the box at the bottom, and ribbed inter-meshing rollers mounted therein of a gear-pinion, meshing 125 with one of the said rollers, a grinding surface actuated from said gear-pinion, and means to adjust the said grinding surface, within said recess, so as to increase or diminish the space therebetween, substantially as set forth.

3. In a paint mixing and grinding machine, 130 the combination with a box, having a recess

communicating with its interior, and a cylindrical bearing recess formed in the said box, of a shaft mounted in said cylindrical recess, and having a grinding surface at its 5 opposite end, and a set-screw passing into said recesses, and engaging a recess in the end of said grinding surface, and a second set-screw extending through a portion of the

box and bearing against the end of the shaft, substantially as and for the purpose set forth. 10

In testimony whereof I affix my signature in presence of two witnesses.

THEODORE G. JOHNSON.
